NURSING BOTTLE HOLDER

Charles C. Riggs, Roscoe, Calif.

Application September 27, 1944, Serial No. 556,037

3 Claims. (Cl. 248—105)

My invention is peculiarly adapted to the positioning and retention of a nursing bottle for infants, and wherewith the bottle is held in secured relation for constant or intermittent use.

An object is to provide a nursing bottle holder that may be conveniently placed in the bed or crib, against dislodgement, yet remain in constant reach of the infant.

A further object of the invention is the provision of a device of said characteristic wherein extra nipples, teething rings, and other small articles for use about the infant may be handily kept.

And a further object of the invention is the provision of a device affording the mother or child's nurse care free attention as the nursing nipple with the bottle holder properly placed, is at all times within reach of the infant's mouth.

I attain these objects by the device illustrated in the accompanying drawing, in which:

Figure 1 is a plan view of the bottle holder;

Figure 2 is a sectional view designated by line 2—2 of Fig. 1;

Figure 3 is a sectional view on line 3—3 of Fig. 2;

Figure 4 is a sectional view on line 4—4 of Fig. 4;

Figure 5 is a sectional view on line 5—5 of Fig. 4;

Figure 6 is a sectional view on line 6—6 of Fig. 4, and

Figure 7 is a plan view showing a modification of the bottle securing buckle means disclosed in the other views.

Similar letters and numerals of reference indicate like parts throughout the several views.

The bottle holder consists of an inverted box like base 10, having a cover 11 which forms the bottom of the holder when positioned for use. The cover 11 is snapped in place in secured relation to the base by a groove 12 provided in the side wall 13, said means comprising but one of many, not shown, for holding the same.

The upper portion of the base herein designated as its top 14, is provided with a cavity or depression 15 shaped to conform to and provide a bed for the nursing bottle B equipped with the conventional nipple N.

The bottle is constrained against movement and dislodgement while thus positioned by suitable retaining means such as a flexible loop 16 made of a flexible elastic member or cord, which, for example, has its respective ends passed through holes 17 provided in the top 14 on each side of the cavity 15.

The ends are secured against withdrawal by suitable means, knots 18, for example, thereby forming the loop 16. Prior to inserting the cord for forming the loop 16 above the top 14, its ends are passed through a slideable buckle 19 comprising a ring 20 and a disk 21 having a tongue or wedge 22 for insertion into the bore 23 of the ring 20. A pair of holes 24 are provided through the disk 21 on each side of the tongue 22. The ends of the cord are passed through the holes 24, thence through the bore 23, whereby a loop 25 is formed above the buckle 19.

A tie cord 26 is securely attached to the rear wall of the base 10 by passing through a hole 27 therein provided, and is knotted as at 28. It provides a means for securing the holder to the infant's bed or crib by tying to the foot end, or it may be pinned to the covers, or fastened to a cross-wise tie line attached to the sides of the crib.

A modification of the buckle means hereinbefore described is shown in Fig. 7. It indicates the buckle 19 as comprising a ring 20 threaded at 29 on its outer periphery to mate with threads 30 provided internally of another ring 31 having a shoulder 32 whereby the disk 21 may be clamped against the ring 20 to grip the loop 25 in co-operation with wedges 22 and ring 20.

With either type of buckle, the modus operandi is the same. Thus, with the bottle positioned on the holder with the loop 16 thereover, the bottle is secured by merely engaging the looped end 25 with a finger of one hand and while exerting a slight upward pull, depressing the disk 21 with the other hand. This draws the cord tightly around the bottle. Reversing this procedure by merely holding the loop portion 25 and exerting an upward lift on the disk, 40 raises the latter and slackens the loop 16 around the bottle.

The holder with the bottle attached is preferably placed beside the infant with the nipple N projecting sufficiently close to enable the infant 45 to readily grasp the same.

The contour of the holder is such that once placed, it will remain in the position desired. The purpose of tying it to the crib merely prevents it from moving upwardly and above the logical nursing position. With a little practice, proper placement of the holder to best serve the infant may readily be ascertained.

Manufactured of plastic or other suitable material, in permanent colors, the conventional baby colors—blue and pink, for example; the holder

is light in weight, rust proof, neat and trim in appearance and washable. It has no objectionable features, and can be produced and sold at no great cost.

My invention may readily be adapted to keep the milk in the bottle warm while positioned on the holder, the mere placement of a conventional heating element within the base connected to a source of electrical energy, and producing the surface area of the cavity or depression 15 in a slotted or grilled effect for conducting the heat to the bottle readily transforming the device into an adequate heating unit.

I am also aware that slight modifications in structure may from time to time be made without departing, however, from the scope of the present invention, and as defined in the claims which are appended hereto. Hence, I do not limit my present invention to the exact description herein disclosed, but what I do claim is:

1. In a nursing bottle holder, a base adapted to be placed in position for holding a nursing bottle in proper proximity to a nursing infant, a flexible element secured to the base so as to form a loop for embracing the bottle and holding it on the base, and a buckle slidable on the loop for releasably constricting the loop around the bottle, including a ring through which the loop passes, a disk having a pair of openings for reception of opposite legs of the loop, and a wedge

member carried by said disk and adapted to extend through said ring in contact with said loop to hold the latter constricted around the bottle for releasably holding the buckle against sliding movement relative to the loop.

5 2. In a nursing bottle holder, a base, a flexible element secured at its ends to said base so as to form a loop for embracing and holding a nursing bottle thereon, a buckle adjustable on the loop for releasably clamping the loop around the bottle, said base being hollow and providing an enclosed storage chamber therein, and a removable wall affording access to said chamber.

10 3. In a nursing bottle holder, a base, a flexible element secured to said base so as to form a loop for embracing and holding a nursing bottle thereon, a buckle adjustable on the loop for releasably clamping the loop around the bottle, said buckle including a ring slidably embracing the outer end portion of the loop, a disk adapted to abut said ring and having a wedge member adjustable on the ring for frictionably gripping the flexible element between it and the ring to lock the ring in position for clamping the loop around the bottle, said ring being externally screw threaded, and a flanged internally screw threaded ring screwed on said ring to hold the ring and disk together and the loop constricted around the bottle.
